DESIGN FOR A STACKING UNIT OR THE LIKE

Ralph Fred Baird, Cincinnati, Ohio, assignor to
The Globe-Wernicke Company, Norwood, Ohio,
a corporation of Ohio

Application February 1, 1940, Serial No. 89,936

Term of patent 7 years

To all whom it may concern:

Be it known that I, Ralph Fred Baird, a citizen of the United States and a resident of Cincinnati, in the county of Hamilton and State of Ohio, have invented a new, original, and ornamental Design for a Stacking Unit or the like, of which the following is a specification, reference being had to the accompanying drawing, forming a part thereof.

In the drawing:

Figure 1 is a side elevational view of a stacking unit or the like, showing my design.

Figure 2 is a rear elevational view.

Figure 3 is a perspective view thereof, looking down from the top.

I claim:

The ornamental design for a stacking unit or the like, as shown.

RALPH FRED BAIRD.
